UNITED STATES PATENT OFFICE.

GEORGE H. SELLERS, OF RIDLEY PARK, PENNSYLVANIA, ASSIGNOR TO THE
EDGE MOOR IRON COMPANY, OF NEW CASTLE COUNTY, DELAWARE.

ART OF UPSETTING AND SHAPING METAL BARS.

SPECIFICATION forming part of Letters Patent No. 372,571, dated November 1, 1887.

Application filed June 25, 1887. Serial No. 242,536. (No model.)

To all whom it may concern:

Be it known that I, GEORGE H. SELLERS, of Ridley Park, in the county of Delaware and State of Pennsylvania, have invented certain new and useful Improvements in the Art of Upsetting and Shaping Metal Bars, of which improvements the following is a specification.

In a patent for improvement in upsetting and shaping metal granted to William Sellers and George H. Sellers, under the date of April 24, 1883, No. 276,291, certain means and methods were shown and described for accomplishing this object--to wit, upsetting metal bars without piling and without folding--pointing out as an essential feature that when the bar requires thickening as well as spreading the thickening and spreading operations must be successive instead of simultaneous, and in the same patent certain means were shown and described whereby the bar would be prevented from bending laterally under the upsetting-pressure. In the Patent No. 291,098, dated January 1, 1884, granted to the same parties, for the method and means therein described for thickening and spreading such bars simultaneously instead of successively, as in the before-mentioned former patent, the same means are shown and described, whereby the bar would be prevented from bending laterally under the upsetting-pressure. In upsetting and shaping metal bars heretofore to form eye-bars for bridges or analogous structures the shaping operation has been performed in a die of the proper form and dimensions from which the surplus metal could flow only in the line of the bar, and consequently it was necessary to cut the bars to the exact length required before the second or last eye was forged, and whether the thickening and spreading was effected successively or simultaneously such bars have always heretofore been very much thickened, in order that a large amount of spreading would result from flattening them in a die of the proper form and dimensions. This flattening operation requires that the metal shall be very hot to enable it to flow with facility, and with iron bars, the final treatment being at a welding temperature, this process produced excellent results; but with steel bars it is essential that the final work shall be given

at a low red heat; and to effect the best results the amount of this work must be such as to produce at the very least a measurable disturbance of the whole mass treated. It is impossible with this metal at the proper temperature to effect the necessary reduction in thickness by subjecting the whole surface to pressure in a die, and pressures upon smaller similar areas within a die fail, because the plunger which transmits them cannot be maintained. Recourse is then had to the steam-hammer and to shifting the piece to be forged so as to treat the whole surface by successive blows without confining it in a die; but it is impossible with this metal to accomplish even this without reheating after upsetting, and frequently several reheatings are required. These reheatings so near the end of the process are under the control of workmen often ignorant of and generally unappreciative of the danger which may result from finishing at a high heat, and of such defects no evidence will remain which the engineer can detect without testing to destruction. Consequently there is a degree of risk and uncertainty about steel eye-bars made in this way which renders such a process unfit for use upon this metal.

The object of my present improvement is to spread and shape bars of iron or of steel at one upsetting operation and to effect a simultaneous thickening, spreading, and shaping at one heat without bending the bar, so as to form sinuous folds.

It is a further object of my improvement to provide dies in which these simultaneous operations can be effected.

It is a further object of my improvement to straighten the upset portion of the bar and bring it to the requisite thickness by successive lines of pressure upon limited areas and without blows.

It is a further object of my invention to provide such thickness of metal when flat bars are to be upset that the bars will not bend laterally under the upsetting-pressure, and that a nearly uniform pressure for the same diameter of eye may be maintained whether the bars are thick or thin, in proportion to the diameter of their eyes; and to these ends my invention consists in thickening, spreading, and

and shaping bars of iron or of steel at one operation by upsetting in dies provided with a lateral outlet for surplus metal.

It further consists in distorting a portion of 5 a flat bar in such manner that a flat side thereof shall be curved transversely or otherwise provided with additional guiding-lines longitudinally, and then upsetting this distorted portion of the bar between dies, the operating-surfaces 10 of which are so arranged as to support the bar in three or more lines.

It further consists in combining with such dies shaping cheek-pieces fixed relatively to each other and a shaping upsetting-plunger, 15 whereby the edges of the bar may be shaped to the desired form as the bar is upset and guided within the dies.

It further consists in providing a pair of 20 rolls between which the upset portion of the bar can be passed back and forth after it has been upset, the upset straightened, and the thickness reduced to that required.

It further consists in heating so much of two 25 or more flat bars as is to be operated upon to the requisite temperature, then placing this heated portion of the bars in a pile within spreading-dies with their flat surfaces parallel to the plane of the upset, then closing the spreading-dies, then upsetting the pile, and 30 then separating the pile into the bars which formed it.

In the accompanying drawings, which make 35 part of this specification, Figure 1 is a sectional side elevation of the upsetting-dies and shaping cheek-pieces. Fig. 2 is an end view of the same. Fig. 3 is a plan of the lower die, showing the shaping cheek-pieces in position thereon and the end of the shaping upsetting-plunger. Fig. 4 is a side elevation of the 40 distorting-bar. Fig. 5 is a sectional end view of the same. Fig. 6 is a front elevation of the rolling-machine for finishing the upset ends of the bars, and Fig. 7 is a side view of the same.

45 The upsetting mechanism best adapted to the application of my present improvements is shown and described in Patent No. 178,966, dated June 20, 1876, granted to me for improvement in machines for welding, upsetting, 50 and shaping iron, and in Patent No. 178,967, dated June 20, 1876, granted to William Sellers for improvement in hydraulic apparatus for holding bars of iron against the pressure required to upset them, and the dies I now 55 show in the drawings, herein referred to, are constructed so as to be operated in such a machine; but inasmuch as the construction and operation of such machines are well understood it is unnecessary to give any detailed description of them herein.

In the before-mentioned Patent, No. 276,291, granted to William Sellers and George H. Sellers, spreading-dies for round bars are shown and described, in which the upset may be effected without bending the bar; but the use of 65 such dies was prior to my present invention confined to round or square bars, because only

such bars could enter the guiding groove or grooves for maintaining the alignment of the bar under the upsetting-pressure to which the 70 bar was subjected between the upsetting-dies.

In the then state of the art it was desirable to thicken all bars materially before spreading them. The thickened bar required that shorter length should be provided for spreading, and 75 with such length no provision was required against lateral bending in flat bars; but with the increasing use of steel, which required a different final treatment from iron, it became very desirable to complete the whole of the 80 work required to form an eye at one heat, so that thereby the final work must necessarily be performed at a low temperature. To this end, the manufacture of steel eye-bars, the use of the flattening-dies for the final operation was incompatible, as they required the metal to be at a high temperature, and it became desirable to spread the bar to the required dimensions and shape without increasing the thickness more than would be due to 85 the spring of the dies under the great pressure to which they would be subjected in the upsetting operation. This thinner upset required a greater length of the unsupported bar to be upset, which I found could not be effected 90 in a thin flat bar without great danger of bending it laterally, and after very many attempts to remedy this difficulty I finally succeeded by introducing a preliminary operation to the upsetting one. This preliminary operation 95 consisted in placing the heated flat bar between the spreading dies for round bars, (shown and described in the before-mentioned Patent No. 276,291,) and then placing on top of the flat bar a distorting bar so shaped on its under side 100 that when the closing pressure was applied to the upper die a portion of the flat bar would be forced into the guiding-groove in the lower upsetting-die. The closing-pressure was then released, the distorting-bar removed, and the 105 dies closed on the distorted bar. Then the upsetting-plunger was operated until the upsetting operation was completed. The groove 110 formed longitudinally by the distorting-bar was filled by the upsetting operation, so that 115 the upset when completed was flat on one side, while a rib was formed upon the other.

That this part of the operation may be more fully explained, I now refer to the drawings, Fig. 1, in which A is the bottom upsetting-die, 120 its upper side being provided with a bar, *dd*, sliding freely therein, whereby the thickness of the upsetting-plunger may be increased, as shown and described in the before mentioned patent, No. 291,098, and in this bar *dd*, I provide the longitudinal guiding-groove *a*. B is the top upsetting-die, which has a plane surface. The distance between the dies A and B determines the thickness of the upset. The shaping cheek-pieces *b* and *b'* are placed between the dies A and B and are of the same, thickness as the flat bar upon which the upsetting-dies are to operate. This is shown more clearly in Fig. 2, and in Fig. 3 is shown the

shape of these cheek-pieces and means for relieving the side pressure thereon after the upset is completed and preparatory to removing the bar from the upsetting-machine, which, as 5 finished, is represented by dotted lines. The shaping cheek-piece *b* and the relieving-block *C* are prevented from moving forward when the upsetting-plunger *D* is operated by the upsetting-ram, as they are arranged to abut 10 against a rib which is provided for holding the dies against the upsetting-pressure in the machine shown in the above-mentioned Patent No. 291,098. The shaping cheek-piece *b'* is sustained laterally by the relieving-block *C* 15 upon surfaces inclined horizontally and against the upsetting-pressure by shoulders which abut upon the relieving-block *C*.

The distorting-bar *E* is shown in side elevation in Fig. 4 and in sectional end view in 20 Fig. 5, and this latter shows the rib *e* on the under side conforming in shape to the groove *a* in the bar *d d* in the lower die, *A*. The cheek-pieces *c c* on each side of this distorting-bar are for the purpose of locating the rib *e* on 25 the distorting-bar in the center line of the flat bar to be operated upon, and the center line of this bar is located over the center of the groove *a* by the concave shape of the upsetting-plunger *D*, against which the end of the 30 bar is thrust, and by the hydraulic clamps on the outside of the machine, before referred to.

The end of the upsetting-plunger *D*, Fig. 3, is shaped to suit the form of upset intended. The under side of this plunger is provided with 35 a rib which fits the groove in the lower die, *A*, upon which the upsetting plunger rests.

The operation is then as follows: A sufficient portion of the bar to be upset is heated to the required temperature and placed within the 40 upsetting dies, its end resting firmly against the plunger *D*, so that the center line of the bar shall be over the center line of the groove *a* in the bar *d d* in the lower die, *A*. The distorting-bar *E* is then inserted above the flat bar 45 and thrust toward the plunger *D* until its motion is arrested by its cheek-pieces *c c* coming in contact with the plunger *D*. The closing-pressure is then applied, and the upsetting-dies are closed upon the distorting-bar 50 and flat bar under it. This latter is by this pressure shaped on its under side to fit the groove in the bar *d d*, and on its upper side to fit the distorting-bar *E*. The closing-pressure is now released, the distorting bar *E* is withdrawn, 55 and the upsetting-dies are again closed, but this time upon the flat bar alone. This closing is limited by the thickness of the shaping cheek-pieces. The upsetting-pressure is now applied to the plunger *D*, which is thereby 60 forced forward the proper distance to give the required shape and size to the upset. Any surplus metal is forced out laterally between the ends of the upsetting-plunger *D* and the ends of the shaping cheek-pieces *b* and *b'*, and 65 may be cut off as soon as the bar is removed from the machine.

The operation of upsetting a round or square

bar is the same as for a flat bar, except that the distorting-bar is not used, as such round or square bars will enter the guiding-grooves 70 in the upsetting-dies described in the above-mentioned Patent No. 276,291. In upsetting such bars the dies may be closed upon the cheek-pieces before the bar to be upset is inserted. The bar can then be inserted only in 75 the line of the guiding groove; but if the dies are open when the bar is inserted it must be so placed that it will enter the guiding-groove when the dies are closed. A sufficient portion of the bar to be upset is heated to the required temperature and placed within the upsetting-dies, its end resting firmly against the plunger *D*, so that the amount of metal to be upset may be the more accurately determined, which can be readily fixed by the position of 80 this plunger. The upsetting-pressure is now applied to the plunger, which is thereby forced forward to give the required size and shape to the upset. Any surplus metal is forced out laterally between the ends of the upset plunger *D* and the ends of the shaping cheek-pieces 85 *b* and *b'*, and may be cut off as soon as the bar is removed from the machine. The upsetting-plunger *D* is supported by the upsetting-ram and secured to it by dowel-pins to draw it back 90 after the upset has been finished, and the shaping cheek-pieces are simply placed in position upon the lower die, the upsetting-pressure retaining them there. Both plunger and cheek-pieces can thus be readily changed to suit different sizes of bars or eyes, these being the only parts requiring change for this purpose, and this can be done in a few minutes, whereby 95 a great saving of time is effected over any process for upsetting and shaping such eyes heretofore used. To remove the bar from the machine, the upsetting-plunger *D* is withdrawn to its original position, the closing-pressure is released from the upsetting dies, and the upper die, *B*, is raised, when a slight blow from a 100 sledge upon the outer end of the bar will drive it and the cheek piece *b'* toward the plunger *D*, which will release the bar from the pressure of the shaping cheek-pieces. The bar can be then readily withdrawn from the machine. 105 The bar may be otherwise relieved from the pressure of the shaping cheek-pieces, after the close of the upsetting operation, by providing a recess wider than the eye in the lower die, *A*, which recess is covered by the bar *d d* during the upsetting operation, for which purpose this bar *d d* must be widened. After the upsetting is completed the bar *d d* may be withdrawn. Then by inserting a block under the upper die, *B*, and imparting a closing movement to this die the bar will be forced downward from the shaping cheek-pieces into the recess below it, from which it can be readily removed. With the construction above indicated the shaping cheek-piece *b'* may be made 115 the same as *b*. It will now be found that the upset end of the flat bar is somewhat thicker than the original bar, owing to the yielding of the several parts in the machine, and that it has a 120

rib upon its under side corresponding to the groove in the lower die. The groove on the upper side of the flat bar that was formed by the distorting bar has been filled up by the upsetting operation. The round or square bar will likewise have a rib on its under side, and it now only remains to punch the hole for the pin in the center of the eye and to remove the rib, before referred to. For these purposes the bar is first taken to the flattening-machine, which machine is provided with the necessary guides for centering and the proper punch and dies, as is well understood, and the proper size of hole is quickly punched. This operation will to a certain extent distort the surface about the hole and may bend the eye; but these defects are removed by the same operation that removes the rib, before referred to. For this purpose I provide a pair of rolls operated by hydraulic mechanism, which will be more clearly understood by referring to Figs. 6 and 7, representing a front and a side elevation, respectively, of the rolling-machine, in which E is the top and F the bottom roll, which are securely held in the housings G and G. These housings are bolted upon shoe-plates to foundations, as in a rolling-mill. The neck of the top roll, E, projects on one side through its housing far enough to receive a gear-wheel, W, upon its overhanging end, and similar provision is made upon the bottom roll, F, to receive a similar gear-wheel, W', upon its overhanging end. These two gear-wheels mesh with racks H and H', united, respectively, to the outer ends of the cross-head I. These racks are placed diagonally to a vertical plane in the axes of both rolls, so that a vertical movement of the racks will cause the contact-surfaces of the two rolls to move in the same direction. Securely fastened upon the top of the housings G and G, I provide the hydraulic cylinder K, having a piston and rod, this latter passing out at the top of the cylinder and securely fastened to the cross head I. Water under pressure is admitted to the ends of the cylinder K through the pipes f' and f'', which connect the top and bottom of the cylinder with the valve-chest L. The admission of the pressure-water and its escape from the cylinder after performing its work are regulated and controlled by a balanced piston-valve in the chest L, operated by the handle M, as is well understood. Threaded in the top of each housing I provide heavy compressing screws N, the lower ends of these screws resting upon the cap-bearings of the top roll, E. Their upper ends are provided with gear-wheels meshing with the spiral pinions O and O' upon the shafts P and P', and these latter are connected by bevel-wheels and pinions with the horizontal hand-wheel shaft Q, so that by turning the hand-wheel the compressing screws N may force down the top roll upon the bottom one or upon anything between them. The top roll, E, is counterbalanced, so as to press against the ends of the compressing-screws N,

by means of the counter-weight R, acting through the levers g and g' and the struts h and h', which latter pass up through the housings and rest against the under sides of the lower boxes or bearings for the top roll, E. A table, S, is provided on the side of the rolls at which the bars are entered, and the rolls are rotated back and forth by admitting the pressure-water alternately above and below the piston in the hydraulic cylinder. To operate upon the upset bar, the rolls are closed to a point slightly in excess of the thickness required. The upset end of the bar is pressed against the rolls and is drawn through by their rotation. The rolls are then further closed to the required thickness, their motion is reversed, and the bar is carried back and out of the rolls a finished product. The above is the usual practice; but, when required, the thickness of the eye may be increased above that of the bar or it may be decreased below it by increasing or decreasing the thickness of the shaping cheek-pieces and shaping upsetting-plunger, as will be well understood by a skillful workman.

The rolls shown and described herein are operated by hydraulic power and are reversible, so as to roll in either direction, as that is more convenient in conjunction with the other hydraulic machinery employed; but a pair of rolls operated by steam or other power, and running always in the same direction, may be used, for which purpose it is only necessary that they should be arranged to open and close conveniently. Such last-mentioned rolls may be closed to the proper distance and the bar to be rolled may be presented so as to be drawn in, or the rolls may be open so as to admit the bar beyond the upset portion, and then by closing them to the desired thickness the bar will be rolled out of the rolls, all of which will be readily understood by a skilled workman.

In the hereinbefore-described process for the manufacture of steel eye-bars time is an important element in obtaining the quality, and the advantage which rolling possesses over any other mode of applying the necessary pressure is that with rolls a narrow line of pressure can be applied, from under which the metal at a low temperature can readily flow, so that the pressure and the time required to obtain the desired thickness is much less, while the condition of the metal and the surface produced is much better than could be obtained by any other mode heretofore practiced.

In the treatment of iron bars the process of upsetting, as hereinbefore described, is followed; but the upset is made somewhat thicker than for steel bars, and, after upsetting, the bar is reheated to a welding heat. It is then transferred to the flattening-machine, as in the before-mentioned Patent No. 276,291, after which it is rolled, as herein described, which brings the eye more nearly to a uniform

thickness than can be done by the flattening-machine, which heretofore has finished the operation.

The preliminary distortion of the flat bar 5 may be effected in a variety of ways. The object of the distortion is to give such flat bars additional guiding-lines longitudinally without restricting the bar from spreading laterally under the upsetting-pressure, and any form of 10 surface transversely other than a plane will answer this purpose. The upsetting-dies themselves may be formed with curved surfaces, or they may be angular, so that they will distort the flat bar in the act of closing with 15 out using the distorting-bar which I have shown and described, and I have used such dies; but they are more complex to construct than the flat die, and they involve a like complexity in the upsetting-plunger, with more 20 extensive changes to suit different sizes of bars and eyes. I contemplate using such shaped dies, however, whenever the character of the work may render it desirable to do so.

In practicing the art of upsetting I discovered that with flat eye-bars the pressure 25 required for upsetting increased rapidly after the diameter of the eye exceeded eight times its thickness. In almost every instance the eyes required exceed this proportion, so that the 30 pressure is largely in excess of that which might be employed were the upset thicker. Moreover, when the upset is thick in proportion to its width, there being less pressure, there is less tendency to bend the bar laterally, and I discovered that when several flat 35 bars of the ordinary proportion were piled together, so that the thickness of the pile was greater than one-eighth the diameter of the eye, the upset could be made between plain 40 dies without bending any of the bars laterally, whereas none of these bars, when taken singly, could be upset to the same diameter of eye in the same dies without bending laterally so much as to render the upset useless for an eye-bar. This discovery was exceedingly important, 45 not only because it enabled me to upset two bars in the same time theretofore required for one with less pressure than might be required for one, while avoiding the liability to 50 bend the bar laterally, but because it enabled me to spread thin bars to a diameter of eye not heretofore attainable by upsetting alone at any pressure. To practice this part of my 55 improvements, the bars, after the proper length has been heated to the requisite temperature, are piled upon each other within spreading-dies, so that the flat sides of the bars will be parallel to the plane of the upset. The thickness of the pile is preferably such 60 that when the closing-pressure is applied to the dies they will close upon the shaping cheek-pieces and the pile of bars at the same time; but the pile may be either thicker or thinner than the cheek-pieces, if desired. The 65 thickness of the upset is determined by the distance between the upsetting-dies; but to

avoid a fin the upsetting dies should close upon the shaping cheek-pieces, so that if the pile is thicker than the cheek-pieces the closing-pressure should reduce it to that of the 70 cheek-pieces.

The bars may be heated separately or they may be piled in the heating-furnace, as they will be in the spreading-dies. In either case care must be taken to have them of uniform 75 temperature; otherwise after the upset pile has been separated into the bars composing it the bars may be found to have varied in thickness. After the heated pile has been placed within the spreading-dies and these dies 80 closed, the upsetting-pressure is applied and the pile is upset and shaped as a single bar. After this operation has been completed, the pile is removed from the machine and separated into the bars which composed it. These 85 bars, if of steel, may then be transferred separately and consecutively to the flatter to be punched and to the rolls to be straightened and reduced in thickness to the required dimension; but if they are of iron they should 90 be first transferred to the heating furnace to be heated to a welding heat, after which they are taken to the flatter to be welded and punched and from thence to the rolls.

It is probable that flat bars very wide in 95 proportion to their thickness might be piled and upset, as before described, without bending laterally when the thickness of the pile was less than one-eighth of the diameter of the eye, but the pressure required would be 100 increased with so thin a pile, and it is not desirable on that account to use a thin pile; but I do not limit my invention to the thickness of the pile.

By upsetting the bars in dies provided with 105 a lateral outlet for the surplus metal I am enabled to take bars cut to length as close as the rolling-mill practice permits, forge the eyes at uniform distances apart, and cut off the surplus metal after the amount of it has 110 been determined by the forging operation, thereby avoiding the delay as well as the liability to error in cutting the bars to the proper length, as heretofore required, in advance of the forging operation. The edges of the eyes 115 from which this surplus metal has been cut present a distinctly different surface from that formed by the shaping cheek-pieces or by the flattening die, or by any forging operation, which difference is sufficient to clearly distinguish such bars from those forged by any process heretofore used.

Having thus described the objects and nature of my invention, what I claim as new, and desire to secure by Letters Patent, is—

1. A spreading-die which determines the thickness of the upset, in combination with shaping cheek-pieces and a shaping upsetting-plunger which shape the edges of the upset and provide a lateral outlet for surplus metal, substantially as described.

2. A spreading-die which supports the bar

in three or more lines, in combination with shaping cheek-pieces and a shaping upsetting-plunger which shape the edges of the upset and provide a lateral outlet for surplus metal, substantially as described.

3. The hereinbefore-described improvement in the art of upsetting and shaping metal bars, which improvement consists in first heating so much of the bar as is to be operated upon to the required temperature, then distorting this heated portion, so that a flat side thereof shall be curved or otherwise provided with additional guiding-lines longitudinally, and then upsetting this distorted portion of the bar while supported in three or more lines.

4. The hereinbefore-described improvement in the art of upsetting and shaping metal bars, which improvement consists in first heating so much of the bar as is to be operated upon to the required temperature, then thickening, spreading, and shaping this heated portion by upsetting it within dies, and then passing this upset portion between rolls which reduce it to the required thickness and give it an even and smooth surface.

5. The hereinbefore-described improvement in the art of upsetting and shaping metal bars, which improvement consists in heating so much of two or more flat bars as is to be operated upon to the required temperature, then placing this heated portion of the bars in a pile within spreading-dies, the flat sides of the bar parallel to the plane of the upset, then closing the spreading-dies and upsetting the pile, and then separating the pile into the bars which formed it.

6. A wrought-iron or a steel eye-bar made by forging the eyes in a spreading-die, which determines the thickness of the upset, in conjunction with shaping cheek-pieces and a shaping upsetting-plunger which shape the edges of the upset and provide a lateral outlet for surplus metal, substantially as and for the purposes described.
